OIL BURNER

Reinhold D. Schoenwetter, Clarendon, Va., assignor to Swirling Heat, Inc., a corporation of Delaware

Application October 5, 1936, Serial No. 104,069

6 Claims. (Cl. 158—28)

This invention relates generally to oil burners, and more particularly to that type of burner adapted for use in furnaces of household heating systems. The specific type of burner contemplated by this invention involves means for imparting to the combustion supporting air stream a violent swirling action which causes the air to commingle with the atomized fuel and thereby to quickly form a combustible mixture that will burn in complete suspension in such a manner that substantial carbon deposits are eliminated. Additionally the invention contemplates means which will divide the air into streams which will pass through a plurality of series of passageways, one group of which causes the air to be directed tangentially against the fuel atomizing nozzle.

Many heating systems in which oil burners are utilized have heretofore been dependent upon refractory bodies for their operation. Such construction retards heating efficiency, increases the cost of operation, and results in the formation of carbon which causes many of the difficulties experienced with such burners. Furthermore prior to initiating operation these refractory bodies are cold and a considerable quantity of oil is required to bring them up to normal operating temperature. This obviously results in an appreciable amount of time being lost before the heat generated can become effective for heating the household.

Normally oil burners sold in industry today are assembled, tested and adjusted at a central plant without regard to conditions under which they are to operate. In practical installations, hardly any two oil burners are installed to operate under the same conditions. The efficiency of burners requiring refractories depends mostly on the size and design of the refractory capable of causing proper commingling of oil and air. The size and design of refractories differ according to size and type of boilers. The refractory is not a part of the burner and its design is left to the questionable skill of the installation man with the result that many burners operate with a low efficiency.

Deflectors for causing the air to commingle with atomized fuel have come into wide use but the provision of an auxiliary deflector which will cooperate with the primary deflector to cause complete suspension has not proved entirely successful especially since they do not provide for the cooling of the atomizing nozzle.

It is therefore an object of this invention to overcome such difficulties as have heretofore been encountered in the use of oil burners.

Additionally this invention has for a primary object the provision of means for so directing the air supplied to the burner head that it will quickly form a combustible mixture with the atomized fuel without the aid of refractory bodies and which will be easy to ignite and will burn in complete suspension without the formation of objectionable carbon.

Another object of this invention is the provision of novel means whereby the volume and velocity of air supplied to the burner head may be controlled to form the best proportional combustible mixture with the atomized fuel.

This invention further contemplates the novel disposition of a group of secondary air passageways in such a manner that a portion of the supplied air will be directed tangentially against the fuel atomizing nozzle to effect a circling motion of air around the nozzle and thereby cool it. The air in its rising circling motion, also serves to lift the stray oil spray into the flame and will cause all of the oil to burn at a distance from the nozzle whereby carbonization of the nozzle is prevented.

Another object of this invention is to provide means for preventing the formation of a partial vacuum in the center of the inverted cone of air which would normally cause the top of the flame to be drawn inwardly and downwardly with the result that the flame would pulsate and be excessively noisy.

This invention still further contemplates the provision of means for compensating for the unequal distribution of oil by the atomizing nozzle which when air is supplied all the way around the burner head uniformly, will cause thin spots in the flame.

Other objects and advantages will appear from the following detailed description when considered in connection with the accompanying drawings wherein:

Figure 1 is a perspective view of a household type furnace with a portion of the wall thereof broken away to show the burner as contemplated by this invention installed therein;

Figure 2 is a vertical elevation of the outer end of the burner showing the prime mover, ignition transformer, fuel pump and air pump or fan casing with a portion thereof broken away disclosing in detail the means whereby the amount of air supplied to the burner head may be adjustably controlled.

Figure 3 is a plan view of the entire burner;

Figure 4 is an enlarged detailed view of the

lower air deflector plate showing the tangentially disposed air passages;

Figure 5 is a vertical elevation of the lower air deflector plate shown in Figure 4;

5 Figure 6 is an enlarged detailed plan view of a modified form of lower air deflector plate showing a plurality of symmetrically disposed vanes;

10 Figure 7 is a vertical section of the modified form of the lower air deflector plate taken along the line 7—7 of Figure 6;

15 Figure 8 is an elevation of the entire burner with the burner head and a portion of the air supply tube in vertical section;

15 Figure 9 is a plan view of the burner with the burner head removed showing the air baffles which serve as a nozzle guide, and also showing the outer end of the burner in horizontal section thereby disclosing the fuel supply conduit and its assembled relationship to the casing;

20 Figure 10 is a bottom plan view of the burner head showing in detail the disposition of the upper air deflector vanes;

25 Figure 11 is a vertical elevation of the burner head showing the top cover which serves as an air director plate partially in section disclosing in detail the means whereby the upper air deflector plate is adjustably spaced from the cover plate;

30 Figure 12 is a vertical section taken along the line 12—12 of Figure 9 showing the fuel supply conduit in cross-section, and the vertical wall which divides the air passageway; and

35 Figure 13 is a vertical section similar to Figure 12 showing a modification of the air blast tube with the vertical wall omitted and the conductors as bus bars.

40 Referring to the drawings in detail, particularly Figure 1, a conventional boiler 10 of the household heating variety is shown with a portion of the side wall thereof broken away to disclose my improved oil burner, indicated generally as 11, in operative position. In this instance the burner head 12 and air tube 13 are inserted through an opening in the bottom door 14 of the furnace. 45 The outer portion of the burner assembly is supported by adjustable legs 15 while the burner head is supported within the furnace by a third adjustable leg 15'. The burner head is preferably positioned centrally with respect to the diameter 50 of the furnace and at an altitude approximating that of the fire grates in the conventional solid fuel burning furnace. This burner, unlike the gun type burners commonly known, is provided with a vertical stationary head adapted 55 to supply the mixture of fuel and air in such a manner that the flame will burn substantially vertically, as indicated in Figure 1, rather than horizontally as with gun type burners.

60 An air pump, blower, or air wheel 17, is mounted on the shaft of a motor 16 and is adapted to be driven by a source of power not shown. A fuel pump 18 having its shaft in substantially axial alignment with that of the motor 16 is connected to the motor shaft and is driven thereby by means 65 of a flexible coupling. Blower 17 supplies combustion supporting air through the air blast tube 13 to the burner head assembly 12. Fuel is pumped from a supply not shown through conduit 19 fabricated of copper, brass or other suitable material, into the strainer chamber 20 from which it is drawn by the rotary pump 18 into the pump chamber. Pump 18 discharges the fuel at a predetermined pressure through pressure controlling valves into conduit 21 which communicates with the conduit 22 leading to strainer

chamber 23 thence to an atomizing nozzle 24. Superfluous fuel delivered to the pressure controlling valves is discharged through an overflow conduit 25 that communicates with the tank or source of supply not shown. The strainer chamber 23 is disposed between the conduit 22 and the atomizing nozzle 24 and carries a fine mesh strainer 26 adapted to co-operate with the pump strainer to free the oil which is fed to the atomizing nozzle 24 from extraneous matter that would tend to clog the orifice 27.

5 The fuel oil is discharged under pressure from the orifice in the form of a jet which if unmolested would be substantially conical in shape. This however is not the case for air supplied by the air pump or blower 17 through the air blast tube 13 is divided and deflected by my improved deflector means in such a manner that a swirling motion will be imparted to it. This causes the combustion supporting air to be more intimately mixed with the atomized fuel to quickly form a combustible mixture.

10 The outer casing for my improved burner head is constructed in two parts, the bottom part 28 being in the form of an upturned elbow that is secured to the air blast tube 13 in a conventional manner. The upturned portion of the elbow is flared and provided with a vertical cylindrical wall 29 on which rests the upper portion 30 of the burner head casing. The upper portion of the burner head casing is so formed as to have a depending cylindrical wall 31 which rests upon the vertical wall 29 of the upturned elbow. The top face of the portion 30 is provided with an opening which cooperates with the deflector band 32 to form a bowl. The deflector band 32 may be given any desired shape.

15 Supported in adjusted spaced relation to the top face of the burner casing 30 by suitable screws 35, is the air deflector assembly which is composed of an upper plate 36 provided with radial vanes 37 around the periphery thereof that cooperate with the cylindrical side wall of the casing to form a group of air passageways. These vanes 37 which perform an important function in the operation of the burner are given a substantial pitch whereby the air forced through the passageways between them will have a swirling motion imparted to it. The air fed through these passageways will strike the inner surface of the top wall of the burner head casing at an acute angle of incidence and due to the continued supply of pressure will be forced inwardly and downwardly in the form of a swirling sheet tending to converge in the vicinity of the atomizing nozzle 24 where it will then be forced upwardly in contact with the atomized fuel.

20 A lower deflector plate 38 is secured to the bottom of the upper deflector plate 36 and functions to keep the atomizing nozzle cool and to cause combustion to take place at a distance sufficiently remote from the nozzle to prevent the formation of carbon. Slots 39 in the upper surface of plate 38 cooperate with the baffle plate 40 clamped between the upper and lower deflector plates by screws 41, to form passageways for a secondary supply of air which is directed tangentially against the atomizing nozzle 24. The size of these passageways is sufficiently large to supply the critical quantity of air required to keep the nozzle 24 cool while the burner is in operation, thereby preventing the formation of carbon. Another purpose or function of the air passing through the passageways in plate 38 is that its circling or swirling motion lifts any stray oil 75

spray into the flame or zone of combustion, thereby preventing the spray from depositing on the nozzle and carbonizing. The air supplied through the passageways in plate 38 has still another function in that it breaks the partial vacuum formed inside of the inverted air cone by the air that is discharged from the burner head after passing through the vanes 37.

The opening in baffle plate 40 is just sufficiently large to admit the passage of that amount of air required to keep the nozzle cool and to aid in the support of combustion in the immediate vicinity of the nozzle. This opening in baffle plate 40 has still another important function in that it causes the air passing through it to rise from the burner head in the shape of a hollow inverted cone. This hollow inverted cone thus formed, however, is of smaller diameter than the hollow cone of the primary air mentioned above. Thus, in effect, there is produced a hollow air cone within a hollow air cone. This distribution of the air causes the oil to burn with a hollow flame.

Lower deflector plate 38 being provided with a centrally disposed opening 41' slightly greater in diameter than the diameter of the atomizing nozzle 24, but having a smaller diameter than that of the strainer casing 23, will, when assembled, contact the strainer casing thereby permitting the atomizing nozzle to project upwardly through the openings in the deflector plates. The upper portion 30 of the burner casing with the deflecting means adjustably secured thereto in assembled spaced relationship is adapted to be detached as a unit from the bottom portion 28 of the burner casing and when replaced is properly aligned by the atomizing nozzle 24 and the opening 41' in the lower deflector plate 38.

Disposed immediately below the detachable burner head assembly are baffle plates 42, clearly shown in Figures 8 and 9, that perform dual functions, namely, to serve as a fuel supply nozzle guide and as means whereby the air blast is deflected vertically to insure a flame that will be symmetrical with respect to the burner head. Deflector vanes 42 are secured in the bottom of the lower portion of the burner casing in any conventional manner such as, for example, by a screw 43.

It will be seen that air passing through tube 13 will strike against the baffle plates 42 and be deflected upwardly in separate strata where it is divided into two groups of paths, the first group being defined by the deflector vanes 37 and the second group of paths being those disposed tangentially with respect to the atomizing nozzle in the lower deflector plate 38.

To obtain the maximum efficiency from a burner of this character, it is necessary to properly proportion the amount of supplied air to the amount of fuel atomized, otherwise one does not obtain complete combustion. In view of the fact that variations in draft caused by stacks of different altitude will cause a greater or lesser suction force to be exerted on the burner head, it is necessary to provide means whereby the amount of air escaping from the burner head may be controlled. This invention therefore also contemplates means whereby the inlet air to the air pump or blower 17 may be regulated as well as the volume and velocity of air that escapes from the head of the burner to support combustion. This is in part accomplished by placing in the inlet duct 44 to the pump, a damper or valve 45 that is pivotally mounted at 46 and 47

inside the mouth of the inlet duct as clearly shown in Figure 8. This damper, due to the action of springs 48 and 49 which are anchored by screws 50 and 51 to the casing of the inlet duct 44, is biased toward the closed position. The setting of the damper is effected manually by means of a thumb screw 52 which extends from without the casing through the tapped hole 53 into engagement with the damper. This construction is clearly shown in Figures 2 and 8.

In conjunction with the damper 45 the air passing through the burner head is further regulated by positioning the deflector plate assembly toward or away from the casing 30 of the burner head. If the burner is to be installed in a system where a stack of excessive altitude is used, considerable natural draft is applied to the burner head and, as a result, a volume of air in excess of that which is normally supplied by the fan or air pump would pass through the burner head and result in an improper combustible mixture with the atomized fuel. On the other hand, if the burner is to be used in an installation that utilizes a relatively low stack, very little natural draft would be applied to the burner head and the combustion would be entirely dependent upon the volume and velocity of the air supplied by the fan or air pump. The objectionable features thus introduced can be eliminated by adjustment of the deflector plate assembly relative to the top casing 30 of the burner head by means of the screws 35. (See Figure 8.)

Further in order to produce a flame that will burn most efficiently, i. e., which will not have thin spots in it, compensation must be made for the unequal distribution of oil by the atomizing nozzle. Unless compensation is made for this unequal distribution of fuel a zone which receives too much air will appear thin, while the remainder of the zone will receive insufficient air to support complete combustion. I have found that such a phenomena will result in a flame one side of which will deposit soot or carbon streaks on the inside of a furnace while the thin side will not give a flame of maximum radiant heat.

To overcome this objectionable feature the upper air deflector plates with their radial vanes are cast or moulded and used in their rough condition. Then by assembling the deflector plate 36 with the upper portion 30 of the burner head and rotating the assembly about its vertical axis while the flame is burning the unevenness of the oil distribution from the nozzle can be compensated for by the uneven air distribution thus produced by the rough upper air deflector plate. Obviously the upper deflector plate including its vanes could be formed in any conventional manner other than by moulding or casting.

A modified form of lower air deflector plate is shown in detail in Figures 6 and 7. This plate differs from plate 38 shown in Figures 4 and 5 in that it is provided with substantially radial vanes 54 very similar in construction and pitch to those around the periphery of the upper deflector plate. The air being forced through the passageways defined by these vanes strikes the bottom of the baffle plate 40 at an acute angle of incidence, in a very similar manner to that described in connection with the upper deflector plate 36, and converges inwardly through the passage formed between the baffle plate 40 and the annular portion 55 of the deflector plate in the form of a swirling sheet to strike against the nozzle 24 to effect a cooling thereof and to cause

combustion to take place at a distance sufficiently remote from the nozzle to prevent the formation of carbon. The air at this point is deflected upwardly where it will lift any loose stray oil spray and commingle with the atomized fuel to aid in causing the flame to burn in complete suspension. The outside dimensions of this modified form of lower deflector plate are the same as those of deflector plate 38 shown in Figures 4 and 10 5 and is adapted to be used interchangeably therewith with equal effectiveness.

As shown in Figure 12, the space within the air blast tube 13 is divided by a vertical wall 56 extending throughout the length thereof and 15 forms a second air passageway 57 through which the conductors comprising insulated wires 58 which supply current to the ignition electrodes 59 may be passed. Such an arrangement obviously would prevent injury to the insulation on 20 the conductors by the fuel nozzle when inserting it in the air blast tube or removing it therefrom.

In Figure 13 is shown a modification in which the vertical wall 56 has been omitted from the 25 air blast tube and in which the flexible insulated conductors 58 have been replaced by substantially rigid bus bars 58' which carry suitable snap-connectors (not shown) to permit their easy insertion or removal.

30 A novel arrangement of means associated with the ignition electrodes whereby they may be adjustably positioned in the zone of ignition from a point outside the furnace is shown. This is being made the subject matter of a separate application and will be set out in detail therein.

Casting 60 which is secured to the outer end of the air blast tube in any conventional manner, is provided with openings 61 and 62. The opening 61 is adapted to be closed by a side of the ignition transformer 63 when secured in operative 40 relationship thereagainst. The other opening 62 in the casing is adapted to be closed by a plate 64 which has an elbow passageway 65 formed therein. Both openings 66 and 67 of the passageway 45 are interiorly threaded to receive conduits 21 and 22, respectively. Plate 64 is held in position by screws 68 and covers an opening which is so disposed that the fuel supply conduit 22, the strainer chamber 23 and the atomizing nozzle 24 50 can be withdrawn as a unit. This obviously is advantageous from a service point of view.

In operation when an electric current is supplied to the motor 16 it drives the blower and fuel pump. The fuel pump supplies fuel oil 55 through pressure controlling valves to the atomizing nozzle at a predetermined pressure. The atomized fuel commingles with the combustion supporting air that is supplied by the blower through the air blast tube 13 over baffle plates 42 60 and finally through the adjustable upper and lower air passageways. Thus a combustible mixture is quickly formed that may be readily ignited and will burn, due to the novel design of the deflector plates, in complete suspension without the formation of objectionable carbon. Then to insure complete combustion and to obtain a 65 flame that will give off the greatest amount of radiant heat the amount of intake air to the blower is regulated by the valve or damper located in the inlet duct to the blower. It will be understood that the lower air deflector plate could obviously be constructed and used without the baffle plate 40 by forming radial apertures therein instead of grooves 39.

70 75 The foregoing description conveys a clear un-

derstanding of the objects prefaced in the opening statements of my invention, and while said description is directed solely toward the construction illustrated, I desire it understood that the privilege is reversed of resorting to all the mechanical changes to which the device is susceptible, the invention being defined and limited only by the terms of the appended claims.

I claim:

1. An oil burner comprising in combination a 10 fuel atomizing nozzle, means for conducting air to and around the axis of said nozzle, air deflector plates disposed coaxially with respect to the axis of said nozzle, and means formed on each of said plates for imparting a swirling motion to the air 15 supplied to said nozzle, the upper surface of one of said plates being substantially in the same horizontal plane as the discharge end of said nozzle and another of said plates being substantially above said plane, whereby air is conducted 20 to fuel sprayed from said nozzle both in the plane of the discharge end of the nozzle and thereabove.

2. In an oil burner, an oil atomizing nozzle, an air conduit delivering air about said nozzle 25 and a detachable head at the delivery end of said conduit, said head comprising a top portion forming an extension of the conduit, air deflector means and means securing said deflector means below said top portion, and said air deflector 30 means comprising an upper air deflector plate having a centrally disposed opening therein, substantially radial vanes on the periphery of the upper air deflector plate forming passageways for a portion of the air supplied to said head, a lower 35 air deflector plate secured to the bottom of the upper air deflector plate and having a centrally disposed opening therein in alignment with the opening in the upper air deflector plate, said lower air deflector plate having substantially 40 V-shaped slots in the top surface thereof disposed in a horizontal plane and tangentially to the opening therein, and a baffle plate secured 45 between the upper and lower air deflector plates forming with the substantially V-shaped slots passageways for directing another portion of the air supplied to said head tangentially against said nozzle to cool said nozzle.

3. In an oil burner, an oil atomizing nozzle, an air conduit delivering air about said nozzle and a detachable head at the delivery end of said conduit, said head comprising a top portion forming an extension of the conduit, air deflector means and means securing said deflector means below said top portion, and said air deflector 50 means comprising an upper air deflector plate having a central opening therein, a plurality of vanes associated with the periphery of said upper deflector plate forming passageways for a portion of the air supplied to said head, a lower air deflector plate secured to the bottom of the upper air deflector plate and having a central opening 55 therein in alignment with the opening in the upper air deflector plate, said lower air deflector plate having slots tangentially disposed with respect to the central opening, a plate overlying said slots and cooperating therewith to form a group of passageways for another portion of the air supplied to said head, said last mentioned portion of air aiding said first mentioned portion of air in supporting combustion and striking said atomizing nozzle tangentially, whereby said nozzle is maintained in a cool state while in operation.

4. In an oil burner, an oil atomizing nozzle, an 70 75

air conduit delivering air about said nozzle and a detachable head at the delivery end of said conduit, said head comprising a top portion forming an extension of the conduit, air deflector means and means securing said deflector means below said top portion, and said air deflector means comprising an upper air deflector plate having a centrally disposed opening therein, a plurality of vanes associated with the periphery of said upper deflector plate forming passageways for a portion of the air supplied to said head, a lower air deflector plate secured to the bottom of the upper air deflector plate and having a centrally disposed opening therein in alignment with the opening in the upper air deflector plate, said lower air deflector plate having slots disposed in the top surface thereof in a horizontal plane tangentially to the opening therein, a plate overlying said slots and cooperating therewith to form a group of passageways for directing another portion of the air supplied to said head tangentially against said nozzle to cool said nozzle.

5. In combination in an oil burner, an atomizing nozzle having a substantially vertical axis and an upwardly directed discharge end, means for supplying oil under pressure to said atomizing nozzle, means for conducting air to said nozzle, substantially circular upper air deflector means arranged substantially concentrically with respect to said nozzle axis and above the discharge end of said nozzle and lower air deflector means arranged substantially concentrically with respect to said nozzle axis and with the upper portion thereof substantially in the plane of the discharge end of said nozzle; each of said air de-

flector means having means disposed therein to direct air passing therethrough toward the nozzle axis in a direction tangential to a circle about said nozzle axis, whereby air is directed about the axis of said nozzle both in the plane of said discharge end and thereabove.

6. In an oil burner, an oil atomizing nozzle, an air conduit delivering air about said nozzle and a detachable head at the delivery end of said conduit, said head comprising a top portion forming an extension of the conduit, air deflector means below said top portion, and said air deflector means comprising an upper circular air deflector plate having a central opening therein, said upper plate being disposed with the said opening about the axis of said nozzle, substantially radial vanes extending from the periphery of said upper deflector plate forming passageways for a portion of the air supplied to said head, a lower air deflector plate secured to the bottom of the upper air deflector plate and having a central opening therein in alignment with the opening in the upper air deflector plate, a baffle plate secured between the upper and lower air deflector plates, said lower air deflector plate having substantially V-shaped slots tangentially disposed with respect to the central opening, said slots and said baffle plate cooperating to form a group of passageways for another portion of the air supplied to said head, said last mentioned portion of air aiding said first mentioned portion of air in supporting combustion and striking said atomizing nozzle tangentially, whereby said nozzle is maintained in a cool state while in operation.

REINHOLD D. SCHOENWETTER.
